UNITED STATES PATENT OFFICE.

JOSEPH KLEPAC AND JARRY KVARDA, OF NEW YORK, N. Y.

RECORDING DEVICE.

1,333,984.

Specification of Letters Patent. Patented Mar. 16, 1920.

Application filed April 22, 1919. Serial No. 291,810.

To all whom it may concern:

Be it known that we, JOSEPH KLEPAC and JARRY KVARDA, citizens of the Republic of Czechoslovakia, residing at New York city, in the county of New York and State of New York, have invented certain new and useful Improvements in Recording Devices, of which the following is a specification.

This invention has relation primarily to recording devices with particular reference to a device for registering, recording or otherwise indicating the dynamic force of a blow or impact applied to any object selected to receive the same.

Another object of the invention is to provide a device of this character which may be utilized to register or record upon any suitable medium the dynamic force which is applied to the keys of a recording piano or other instrument for the purpose of securing a record for subsequent reproduction of the amount of dynamic force applied to the keys thereof when the same is played by an artist whose playing it is desired to record, thus obtaining that great desideratum, namely, expression in the resultant record whereby the exact playing in the minutest detail of the artist may be mechanically reproduced.

Another object of the invention is to provide a device of this character which includes a delicately supported movable member designed to sweep over a series of segments and to complete an electrical circuit through the last segment contacted to cause actuation of an electrically operated recording device, means however being provided to insure completion of the circuit only when the member comes to rest at its limit of movement so as not to actuate any other recording device than the one corresponding to the position assumed by the member at its limit of movement.

In addition to the foregoing, this invention comprehends improvements in the details of construction and arrangement of parts, to be hereinafter described and particularly set forth in the appended claims.

In the accompanying drawings in which similar and corresponding parts are designated by the same character of reference throughout the several views in which they appear,

Figure 1 is a view in side elevation of the indicating portion of our device.

Fig. 2 is a view thereof in horizontal section with wiring connection.

Figs. 3 and 4 are sections taken on the line 3-3 of Fig. 2.

Fig. 5 is a view of a fragment of a paper record for reproducing pianos and fragments of a similar record made with our apparatus.

Fig. 6 is a view in side elevation of a piano action and our device associated therewith.

Fig. 7 is a view showing how the device may be associated with a piano key.

Fig. 8 shows another method of associating the device with a key.

Fig. 9 is a diagrammatic view showing a modification of our apparatus, and

Fig. 10 is a view of a fragment of a record made with our modified apparatus.

With reference to Figs. 1-4 of the drawings, 10 indicates a quadrant shaped plate and 11 a bracket mounted substantially centrally relative to the curved edge thereof to pivotally support a primary member or lever 12. A hammer head 13 is mounted upon one end of the lever and a weight 14 upon the other, said weight being slidably toward and away from the pivot to balance the lever. A series of contacts or segments 15 are arranged circumferentially upon the face of the plate, and a metallic flange 16 is mounted upon the edge of the plate with a right angle portion 17 directed toward the contacts. A light switch arm or secondary member 18 is pivotally mounted upon the bracket 11 for movement about the center of movement of the lever 12, and a spiral spring 19 is provided having its inner end anchored and its outer end secured to the arm to retain the latter in engagement with the lever 12. A weight 20 is shiftable mounted on the arm 18 for a purpose to be presently seen, and a transversely extending cylindrical contact member 21 is mounted near the extremity of the arm to engage the contacts when the arm is moved laterally, being however normally out of such engagement. It will be noted that the contact member 21 rests upon a cushion mounted on the lever 12, the latter thus affording a support for the arm. A pawl 22 is pivotally

mounted on the arm 18 for a purpose to be presently seen, and a transversely extending cylindrical contact member 21 is mounted near the extremity of the arm to engage the contacts when the arm is moved laterally, being however normally out of such engagement. It will be noted that the contact member 21 rests upon a cushion mounted on the lever 12, the latter thus affording a support for the arm. A pawl 22 is pivotally

mounted upon the extremity of the arm 18 to extend transversely thereof and in engagement with the inner surface of the portion 17 of the flange, said portion having a plurality of notches 23 formed therein, one notch opposite each contact 15. A light spring 24 mounted on the member 21 engages the pawl to urge the pawl against the notched flange. The hammer head rests 10 upon a cushion 25 and a stop 26 may be provided to limit upward movement thereof.

It will be apparent that if a blow is directed upon the primary member or lever 12 to urge the same upward the switch arm 18 or secondary member will be carried with it until the head 13 engages the stop 26 whereupon the member 18 is free to continue upward under its own inertia until gravity overcomes its inertia and it returns to normal position. The highest position reached by the member 18 will indicate the force of the blow. The impact may be applied downward upon the hammer head and the rebound thereof will cause the arm 18 to fly upward. There are many ways in which the blow whose force is to be determined may be received upon the lever, and several examples will be given later. The essential object is to cause the lever 12, and arm 18 to travel upward and to bring said arm successively opposite the segments 15. As stated the maximum height reached by the end of the arm indicates the force of the blow. To record this fact we may provide an arrangement consisting of a plurality of electromagnets, one of which is shown at 27 having one terminal connected to the flange 16 and the other to one of the segments. Thus, an electro-magnet is provided for each segment and connected thereto, all of said magnets however being connected in common to the flange 16. An armature 28 is provided for each magnet, being pivotally mounted and provided at its opposite end with a stylus or other recording instrument to make a mark or puncture upon a strip of uniformly moving paper 29.

It will be obvious that if the lever 12 is struck the arm 18 will travel along the series of contacts 15 and the pawl 22 will slide along the notched flange 17 assuming the position shown in Fig. 3. As soon as the arm 18 has reached its upward limit of movement and begins to descend the pawl 22 will engage in the next lower notch and as a result thereof the arm 18 will travel along the series of contacts 15 and the pawl 22 will slide along the notched flange 17 assuming the position shown in Fig. 3. As soon as the arm 18 has reached its upward limit of movement and begins to descend the pawl 22 will engage in the next lower notch and as a result thereof the arm 18 will be shifted laterally toward the segments causing the 65 contact member 21 to engage the segment

directly opposite the notch 23 in which the pawl is engaged as shown in Fig. 4. A circuit will then be completed through a source of current provided and through the flange 17, thence through the pawl 22 and arm 18 70 to the contact member 21, thence entering the segment 15 engaged by said contact member and then passing through the associated electromagnet 27 back to the source of current, thereby energizing said electromagnet causing the armature 28 to rise and consequently carry the stylus downward into engagement with the strip of paper. It will be obvious that the mark upon the paper will be spaced away from the margin 80 to a distance corresponding to the distance upward through which the arm 18 travels, the lowermost segment being connected with the electromagnet adjacent one margin of the paper and the uppermost segment connected to the electromagnet adjacent the opposite margin, the other segments being associated with the magnets lying intermediate therebetween. Other recording devices than that set forth herein may be employed to advantage and hence we do not desire to limit ourselves to the specific form of recording mechanism nor to recommend this in preference to any other. It will be noted that the lowermost segment is located opposite the stop 26 thereby permitting the secondary member to travel upward for some distance before recording a contact. This is to prevent very light blows from being recorded, and the apparatus may be adjusted 100 to operate under any minimum of force desired by adjusting the weight 20 and spring 19. It will be apparent that the inertia and center of gravity of the arm 18 may be varied by shifting the weight toward or 105 away from the center, the spring being adjusted to retain the arm normally in lowered position. The weight 14 should also be adjusted to balance the lever.

In view of the foregoing it will be obvious 110 that this device is eminently adapted for use in connection with recording piano music and to illustrate the manner in which it is used we have shown in Fig. 5 a fragment of a conventional automatic piano record shown 115 at 30 and at opposite sides thereof strips 31 and 32 containing recordations performed by our apparatus. By reference to Fig. 5 it will be seen that the record 30 is divided longitudinally for the purpose of illustration to separate the bass notes which are on the left hand from the treble which are on the opposite side. By reference to the perforations shown it will be seen that a chord may be held for a period covering a number 120 of different notes in the treble clef. To illustrate the manner in which the strip 31 or bass strip is recorded to show the force 125 of the blows used to strike the bass notes on the recording piano it will be noted that 13

the mark indicated at 33 indicates the force of the blow used to strike the chord indicated by the perforations 34. Since the mark 33 is adjacent the center of the strip 31 this indicates that the blow is of a medium force. On the other hand, the mark indicated at 35 used to indicate the force of the blow to strike the chord shown by the perforations 36 would indicate that the blow 10 was moderately soft. With reference to the strip 32 it will be seen that the run indicated by the perforations 37 in the treble clef vary in loudness increasing with each note to a maximum point and decreasing with each 15 note as shown by the series of recordations at 38 in the strip 32. The remaining notes at the treble clef indicated at 39 are at different points along the chromatic scale but obviously are each struck very softly and 20 with the same force as shown by the recordations 40 which are all located adjacent the left hand margin of the strip 32 and in longitudinal alinement. For the purpose of convenience we have shown two strips to indicate the recordation for the bass and treble 25 clefs, although it will be obvious that only one strip may be employed if desired. Furthermore, the use of a separate strip may be obviated by making the recordations directly 30 upon the master record or strip 30, and the recordations may be formed adjacent the perforations as shown at 41, the location of the mark or puncture relative to the length of the slot or perforation indicating the 35 force of the blow used to strike a note or chord.

These records made by our device may be duplicated from the master record to form any number of copies, and these copies are 40 used in automatic player pianos of the type in which a pneumatic or other means is provided to vary the volume of the sound, by regulating the volume of air passing to the hammer actuating means. Since these devices are well known it is not considered necessary in this application to set forth the details of construction thereof as it will be perfectly obvious to anyone skilled in this art how these records may be utilized. 45 To illustrate how the registering and recording device described above may be embodied in a piano of the type used to record the master record we refer to Fig. 6 in which a hammer action for a horizontal piano is set forth in detail. The string is indicated at 42 and the hammer at 43. The hammer is actuated by means of the key, the rear end of which is indicated at 44. Since the construction and operation of a horizontal 50 piano action is well known it is unnecessary to go in detail any more than to state that the hammer head is connected by means of a link 45 to an arm or lever 12^a corresponding in function and nature to the lever 12 described above. The arm 18^a travels over

the plate 10^a which is semicircular in this instance. It will be apparent that when the key 44 is struck the hammer 43 will be carried upward to thereby carry the lever 12^a and arm 18^a until the hammer contacts with 70 the string suddenly bringing the lever 1^a to rest. The arm 18^a will however continue upward under its own inertia through a distance along the support 10^a corresponding to the dynamic force used in striking the key 75 44. Through the medium of the electrical mechanism described above a record will be made upon a strip of moving paper or other medium to indicate the force of the blow used to strike that particular note. A mechanism of this kind is used for each piano key. It will be noted that in this case the string 42 serves as a stop in lieu of stop 26. Thus, when the hammer engages the string the lever 12^a will be suddenly brought to rest 80 85 while the arm 18^a will continue upward and register in the manner described. It will also be obvious that any movable part of the piano action may be utilized to perform the function of the arm 12 or 12^a by suitably associating therewith an arm 18 since the part of the piano action selected will act as the primary arm to carry up the secondary arm and hence we do not wish to limit ourselves to the specific manner of associating the device 90 95 with a hammer shank as shown in Fig. 6 but desire to claim the association of our registering mechanism with any movable part of the piano action. It will also be noted that it is not necessary that the axes of the arm 18 100 and the part of the piano action associated therewith correspond as the device will operate if the axes are displaced relative to each other. 105 In Fig. 7 another arrangement is set forth in which the key 44 is connected directly at its forward end by means of a link 46 through the lever 12^b of the registering device. In this instance however the link 46 is connected to the lever at a point between 110 the fulcrum thereof and the weight 14^b. A still further modification is shown in Fig. 8. In this instance the use of a lever corresponding to the lever 12 is obviated except in so far as the key would function in 115 a manner corresponding to said lever only an arm 18^c being employed which carries the pawl and other mechanism for making contact with the segment 15^c. The arm 18^c is mounted on the key 44 and normally rests 120 in a lowered position upon the cushion support 25^c, and it will be obvious that when the key is struck the rear end thereof is carried upwardly rapidly and when it comes to rest the arm 18^c by its own inertia 125 will be carried upwardly and the contact member 21^c will engage one of the segments 15^c mounted on the plate 10^c which rests upon any suitable support and consequently cause actuation of the recording mechanism 130

to indicate the force of the blow applied to the key.

We have also illustrated in Fig. 9 a modified form of mechanism used to record the force of a blow applied to a piano key when the record or copies made are to be used in an automatic piano player not provided with a pneumatic means to vary the volume of sound. In this instance the device consists of a plate 10^a carrying a plurality of segments 15^a, each being electrically connected to an electromagnet 49 in circuit with a source of current and with a lever 12^a which is delicately mounted and provided with a counter weight 14^a. A light arm 18^a corresponding in function to the arm 18 is provided to travel along the segments. An armature 53 carrying a recording stylus 54 is provided to make a record upon the strip of moving paper 55. The arm 18^a is provided with a pawl mechanism similar to the switch arm described above, but it is adapted to contact constantly with the segments 15^a and successively one after another both during the upward and downward movement of the arm. The arm 12^a is actuated by means of a link 56 connected to a piano action or any other means desired to urge the outer end of the arm upward and it will be obvious that as the segments 15^a are successively contacted thereby one after another of the bank of magnets 49 will be energized to attract its corresponding armature to record upon the paper and as a consequence a series of indications will be made upon the strip shown in Fig. 10. Thus, if the blow struck was particularly hard a maximum length of indication will be made as shown at 57 since every one of the electromagnets 49 will be energized. On the other hand, if the blow is light perhaps only one or two of the electromagnets 49 will be energized and consequently the mark will be short as shown at 58. This record may be made upon a separate strip or may be made directly upon the copy of the record to be used in the automatic player piano and the lever or other means used to move the hammer bar is manipulated. Thus, the lever to manipulate the hammer bar will be moved over to one side as far as possible when a line of the length indicated at 52, comes to view upon the record during movement thereof, or conversely the lever will be moved over to the opposite side to a maximum point when a short line as at 58 appears. If desired a resultant curve may be inscribed upon the record which travels along or corresponds to the contour shown by the right hand end of the marks 57 and 58 and this curve may be used in connection with an indicator or other similar device employed to enable one to vary the volume of sound in automatic player pianos.

65 Thus, it will be seen that we have pro-

vided a novel form of mechanism which in its essentials consists of a movable arm, delicately mounted to be carried upward by its own inertia as a result of a blow imparted directly thereto or to some associated mechanism, and a means of any type desired to record the amount of travel of the arm upon any suitable medium. How this record is utilized to practical advantage to reproduce in an automatic player piano the strength 70 of the blow applied to each note by an artist who performs upon a recording piano does not constitute the subject matter of this application but is set forth in detail elsewhere and hence we do not desire to limit ourselves 75 or to describe any particular mechanism for accomplishing this purpose. It is sufficient to state that with the use of the registering and the recording mechanism described above in its various forms it is possible to 80 produce a record which when reproduced into copies and said copies are used in an automatic player piano provided with the necessary pneumatic elements, will reproduce faithfully the volume of sounds 85 originally produced by the artist in making the record or more specifically, the force of blow applied with each note, and thereby results in the production of what is known in musical technic as "expression" which heretofore has not been obtained with any degree of success by any piano recording or 90 reproducing mechanism.

While we have illustrated and described our invention with some degree of particularity, we realize that in practice various alterations therein may be made. We therefore reserve the right and privilege of changing the form of the details of construction or otherwise altering the arrangement of the correlated parts without departing from the spirit of the invention or the scope of the appended claims.

Having thus described our invention what we claim as new and desire to secure by 100 United States Letters Patent is:

1. A device for indicating the dynamic force of a blow, a support, a lever pivotally mounted thereon for movement in a vertical plane, a weight on said lever to balance the 115 same, an arm mounted for rotation about the axis of rotation of the lever and adapted when engaged by the latter to move upward to a distance corresponding to the force of the blow applied to the lever.

2. In a device for indicating the dynamic force of a blow, a support, a lever pivotally mounted thereon for movement in a vertical plane, an adjustable weight for balancing the lever, an arm pivotally mounted on the 125 support for movement about the axis of rotation of the lever, said arm normally resting upon the lever, and means for changing the center of gravity of the arm whereby when the lever is struck the movement transmitted 130

to the arm will cause the latter to move upward to a distance corresponding to the force of a blow.

3. In combination with a piano hammer, a delicately mounted movable member, and means connecting said member with the hammer whereby when the hammer is moved under the force of a blow the member will be moved to a distance corresponding to the 10 force of the blow.

4. In combination with a piano hammer, a delicately mounted arm movable over a support, and means operatively connecting the hammer with the said members in such 15 manner as to cause the arm to move a distance corresponding to the force of a blow applied to the piano key or said hammer.

5. In combination with a piano hammer, a support, a delicately mounted arm movable vertically upon said support, means for varying the center of gravity thereof, and means connecting said hammer with said member whereby said member will be moved to a distance corresponding to the force of a 25 blow when the piano key or said hammer is moved.

6. In combination with a piano hammer, a vertical support, a balanced lever pivotally mounted thereon for movement in a 30 vertical plane, a delicately mounted arm engaged by the lever, and means connecting said lever with the hammer whereby when the key or hammer is struck the lever and arm will be moved upward until the hammer 35 engages the string and the arm continues upward under its own inertia, to a distance corresponding to the force of the blow.

7. In combination with a piano including a key, of a support, a delicately mounted 40 arm adapted for movement in a vertical plane, and means connecting said arm with the key whereby said arm will be moved to a distance corresponding to the force of a blow applied to the key.

45 8. In combination with a piano including a key, an arm delicately mounted on said key for movement in a vertical plane whereby when the key is struck said arm will be moved by its own inertia to a distance corresponding to the force of the blow.

9. In a piano, the combination with the key and action of a delicately mounted arm mounted on the key for movement in a vertical plane whereby when one end of the key 55 is depressed and the arm carrying end elevated and the hammer strikes the string the arm will be carried by its own inertia to a distance corresponding to the force of the blow.

60 10. In a recording device, a weighted lever mounted for oscillation, a delicately mounted switch arm movable by said lever, a plurality of contacts in the path of movement of said arm, a plurality of electrical 65 recording mechanisms one for each contact

associated therewith, said arm being movable on the impact across the contact, and means operable when the arm comes to rest for engaging the same against the adjacent contact member to complete a circuit 70 through the associated recording mechanism.

11. In a recording mechanism, a weighted lever mounted for oscillation, a delicately mounted switch arm and carried by said 75 lever, a plurality of contacts in the path of movement of the arm, said arm being also movable laterally toward and away from the contact, a plurality of electrically operable recording mechanisms one for each contact in circuit therewith, means for engaging the lever to act by impact and rebound to cause the switch arm to travel across the faces of the contacts, to a distance corresponding to the force of the impact, and 80 means operable when the switch arm has come to rest and begins to return to immediately move the switch arm laterally to engage the same against an adjacent contact to complete the circuit through the 85 associated recording mechanism.

12. In a recording mechanism, a plurality of spaced segments, a balanced lever switch arm carried by the lever and adapted to sweep across the face of the contacts, said 95 arm being movable laterally, a pawl carried by said arm, a flange forming a guide for the pawl, and a plurality of electrically operable recording mechanisms, one for each contact in circuit therewith whereby when 100 the switch arm and lever are moved upwardly and said arm begins to return after reaching its limit of movement said pawl will oscillate to direct the arm laterally to engage an adjacent contact and thereby 105 complete a circuit to its associated recording mechanism.

13. A recording device, a vertical plate, an overhanging flange along the edge of said plate, a balanced lever a delicately 110 mounted switch arm carried by the lever a plurality of contacts adjacent the flange, said flange having a plurality of notches one notch opposite each contact, a plurality of electrically operable recording mechanisms one in circuit with each segment and in common circuit with the flange, and a pawl mounted on the arm and normally engaging the notched surface of the flange whereby when the arm and lever are urged 115 upwardly and the arm begins to return after reaching its limit of movement said pawl will engage in an adjacent notch and direct the arm laterally against an adjacent contact to complete a circuit through the 120 associated recording device.

14. In a recording mechanism, a delicately mounted member, a plurality of contacts in the path of movement of the arm, a plurality of electrically operable record- 130

ing mechanisms one for each contact, said arm being movable across the contacts by impact and returnable after reaching its limit of movement and means operable when said member has reached its limit of movement and begins to return to engage the same against the contact to complete the circuit through an associated recording mechanism.

10 15. In an indicating device, a lever, adjustable means for balancing the same, an arm mounted for movement about the center of movement of the lever, a spring engaging the arm to retain the same in engagement with the lever, and means for changing the center of gravity of the arm.

15 20 25. In an indicating device, a primary arm mounted for oscillation, adjustable means for balancing the same, a secondary arm mounted for movement about the center of oscillation of the primary arm, an adjustable spring engaging the secondary arm to retain the latter in engagement with the primary arm, means for varying the center of gravity of the secondary arm, the primary arm when struck being adapted to carry the secondary arm with it, and means for limiting such movement of the primary

arm whereby the secondary arm may be carried along by its own inertia to register 30 the force of the blow.

17. A movable means to receive an impact, a plurality of recording mechanisms, and means operable by and in proportion to the extent of movement of the impact receiving device to select one of said recording mechanisms and to actuate the same.

18. A strip of record receiving medium, a plurality of recording mechanisms to record upon said strip at various points upon 40 one margin of the strip to the other, an impact receiving member, and means operable upon movement of said impact receiving member and in proportion thereto to select and operate one of the recording mechanisms whereby a mark will be applied upon the medium and by its position relative to the margin of the strip indicate the force of the impact.

In testimony whereof we affix our signatures in presence of two witnesses.

JOSEPH KLEPAC.
JARRY KVARDA.
